CATHODE FOR MAGNETRONS

Original Filed Nov. 7, 1944

UNITED STATES PATENT OFFICE

2,481,061

CATHODE FOR MAGNETRONS

Homer G. Anderson, Newtonville, Mass., assignor
to Raytheon Manufacturing Company, Newton,
Mass., a corporation of Delaware

Original application November 7, 1944, Serial No.
562,334. Divided and this application August
20, 1947, Serial No. 769,705

2 Claims. (Cl. 250—27.5)

1

This invention relates to electron-discharge devices, and more particularly to electron-discharge devices of the magnetron type employing indirectly-heated cathodes.

In devices of the general character referred to, it has been found that interaction between the magnetic field established by the current flowing in the cathode heater wire and the magnetic field established transversely of the discharge path between the cathode and anode is detrimental to the proper operation of the device.

It is, therefore, the main object of this invention to eliminate the aforesaid interaction between the aforesaid magnetic fields.

This object and such others as may hereinafter appear will be best understood from the following description, taken in connection with the accompanying drawing of one embodiment of the invention herein presented for illustrative purposes.

In the drawing:

Fig. 1 is a vertical section through an electron-discharge device embodying one illustrative embodiment of the invention;

Fig. 2 is a cross-section on line 2—2 of Fig. 1;

Fig. 3 is an enlarged vertical section of the cathode on line 3—3 of Fig. 4, showing the connection of the upper lead-in conductor to the upper end of the rod supporting the heater wire and to the protective disk between the upper end of the cathode and the top cap of the device; it also shows the heater wire in elevation; and

Fig. 4 is a cross-section on line 4—4 of Fig. 3, showing the connection of the lower lead-in conductor to the protective disk between the bottom cap of the device and the lower end of the cathode.

The invention is herein illustratively shown and described in its application to that type of electron-discharge device known as a magnetron.

The illustrative embodiment of the present invention shown comprises a cylindrical envelope 2, hermetically sealed at both ends by caps 4 and 6. Said envelope and caps may and preferably will be made of copper. Upon the inner surface of said envelope there is provided a central, circular projection 8 to which are soldered a plurality of suitably spaced, radially disposed plates 10, the inner ends of which constitute anode faces. Said plates 10 will preferably be stamped from a sheet of highly conductive copper. Said anode faces cooperate with a cathode 12 supported substantially centrally of said anode faces, said cathode being preferably of the indirectly-heated, thermionic type, and comprising a conductive sleeve 14 of nickel or other suitable conductive material coated with a coating of barium and strontium

2

oxide or other suitable electron-emissive material.

The cathode 12 contains a helically wound insulated heater wire 16 (see Fig. 3) supported by a conductive rod 18, the opposite ends of which are mounted in insulating washers 20, 24 in the opposite ends respectively of said sleeve 14. In accordance with the present invention said helically wound heater wire 16 is wound clockwise throughout a part of its length and contra-clockwise throughout another portion of its length (see Fig. 3). Herein the winding in one direction is equal to that in the opposite direction. This serves to neutralize the objectionable effect of the magnetic field generated by the heater wire, by causing it to be exerted in one direction by one half of the wire and in the opposite direction by the other half so that diversion of the magnetic field generated by the two pole pieces 12 and 14 from its correct direction and displacement of said heating wire are avoided. Herein the upper end of said heater wire is electrically connected to said supporting rod 18, the other end of said heater wire being electrically connected to the conductive cathode sleeve 14.

A lead-in conductor 26 is sealed through a glass seal 28 mounted at the outer end of a conducting pipe 30 which extends through the wall of said envelope 2 and is hermetically secured therein adjacent the lower end thereof. A second lead-in conductor 32 is sealed through a similar glass seal 34 mounted at the outer end of a conducting pipe 36, also hermetically secured in the wall of said envelope 2 at the upper end thereof.

Light, protective shields 38 and 40, respectively, of tantalum or other suitable material are provided between the upper end of the cathode 12 and the envelope cap 4, and between the lower end of said cathode 12 and the envelope cap 6. These shields prevent electron beams from being projected outwardly from said cathode toward said two envelope caps 4 and 6. The edges of the thin shields heretofore used for this purpose were rough and relatively sharp, which were liable to cause sparking. The present invention contemplates the provision of means for preventing such sparking. In accordance with the present invention this is conveniently accomplished by welding a metal ring 42 to the marginal portion of one side of the shield substantially as shown in Fig. 3, thus increasing the thickness of the edge surface. Said ring 42 also serves the further useful purpose of reinforcing the thin shield and rendering it more rigid.

In the illustrative embodiment of the invention shown in the drawing, the lead-in conductor 32

is connected to said shield 38 by a bracket or support consisting of a conductive wire bent back upon itself at 44 (see Fig. 2) so as to form two substantially parallel arms 46, each presenting a U-shaped formation 48 and a lesser U-shaped formation 50, the latter also substantially parallel to each other but in planes at right angles to the plane of the U-shaped formations 48, and between the latter and the bend 44. The free ends of the two arms 46 are welded to the lead-in conductor 32 and said arms are also welded at the points 52 (see Fig. 2) to the reinforced edge of the shield on the underside of the latter, the bend 44 of said arms being welded to the opposite edge of said shield at 54 (see Fig. 3). The lesser U-shaped formations 50 are welded to opposite sides of the upper end of the aforesaid heater wire 16 supporting rod 18 projecting from the upper end of the cathode 12, thus electrically connecting said lead-in wire 32 to said heater wire 16. The lesser U-shaped formations 50 provide the required spacing of said wire arms 46 and said shield 38 from the top of the cathode 12.

The lower shield 40 is electrically connected to the cathode sleeve 14 by metal supports 56 welded to the lower edge of said cathode and to the reinforced edge of said shield 40, said shield being in turn connected to the lead-in conductor 26 by two wire arms 58 and 60 having one end welded to said lead-in conductor and the other end welded to the reinforced edge of said shield 40. These wire arms are provided with substantially U-shaped formations 62. These U-shaped formations 62 and the above-mentioned U-shaped formations 48 provide for the extension or contraction of the wire connections between said shields 38 and 40 with their respective lead-in conductors as may be necessary to span the distance separating said shields from their corresponding lead-in conductors, should said distances vary.

The above-described connections between said lead-in conductor 32 and shield 38 and the upper end of the heater-wire supporting rod 18, on the one hand, and the lead-in conductor 26 with said shield 40 and the cathode 12, on the other hand, provide the necessary electrical connections of said two lead-in conductors with said heater wire and with the cathode, it having already been stated above that one end of said heater wire 16 is electrically connected to said rod 18 and the other end of said heater wire is connected to said cathode sleeve 14.

A coupling loop 64 extends into the space between two of said plates 10, one end of said loop being connected to the inner end of a conducting pipe 66 hermetically sealed through the wall of the envelope 2, substantially midway between the ends thereof, the other end of said loop being connected to a conductor 68 extending through said pipe 66 and sealed through a glass seal 70 at the outer end of said pipe 66. An additional conducting pipe, not shown, may be electrically connected to said pipe 66 to form with said conductor 68 a concentric line through which the high frequency oscillations generated by the device when it is energized and placed between magnetic poles 72 and 74 may be conducted to a suitable utilizing circuit.

The firm support for the shield provided by welding the wire support to the shield at a plurality of points, for example, three suitably spaced points 52, 52 and 54, precludes any buckling, bending, tilting or other displacement of said shield from any cause.

As already pointed out, the shields of tantalum or any other suitable material may be used. For some cases nickel is particularly desirable, but, owing to its liability to distortion in a magnetic field, shields of this metal have heretofore not proven very satisfactory. The firm support afforded the shields by the present invention, however, has overcome this difficulty and made the use of nickel shields not only perfectly feasible but desirable in certain cases.

The above-described connections also, while affording a sturdy and reliable support for the cathode by said lead-in conductors, do not objectionably affect the temperature of the cathode, for while a certain amount of heat will be withdrawn from the cathode by the shields, the amount so withdrawn in the present instance is an advantage, it being neither too little nor too much.

The present invention enables shields 38 and 40, and the wire supports for the latter, to be assembled and welded in their proper positions to the cathode structure before the cathode is placed in the tube. The operator can thus make sure that the shields and other parts are correctly assembled and properly positioned before placing the assembly in the tube. The welding of the free ends of the wire supports to the ends of the lead-in wires is all that remains to be done and this can be accomplished without any risk of disturbing the assembly in the tube. The shields are supported in such manner that any change from the position in which they have been adjusted before being placed in the tube is practically impossible, whether by magnetic attraction or any other causes. The same applies to the heater wire, the winding of which in opposite directions neutralizes any effect the magnetic field created by said wire might have upon that of said pole pieces and precludes any displacement of said heating wire by magnetic attraction by said pole pieces.

It will be noted that the coils of the resilient heater wire are in close contact with the interior lateral wall of the cathode. It will also be noted that the last coil of the closely coiled wire at one end rests against the disk 21 welded to the inner surface of the cathode and carrying the ribbons 23 that hold the insulating washer 24 in place, and that the last coil of said heater wire at the other end of the coiled wire rests against the disk 55 welded to the inner surface of the cathode. The closely coiled heater wire 16 is thus braced both longitudinally and transversely within the cathode and cannot be displaced whatever the position of the cathode may be, whether vertical or horizontal, and the coils of said heater wire are distributed uniformly throughout the length of the cathode, thus ensuring even heating of the cathode throughout its length.

Wherever the term "a plurality" is used, it is to be construed as meaning "two or more."

I am aware that the present invention can be embodied in other specific forms without departing from the spirit or essential attributes thereof, and I therefore desire the present description to be considered in all respects as illustrative and not restrictive, reference being had to the appended claims rather than to the aforesaid description to indicate the scope of the invention.

This application is a division of my Patent No. 2,439,786, published April 20, 1948.

What is claimed is:

1. An electron discharge device of the magnetron type, comprising: a cathode structure; an anode structure, incorporating a cavity reso-

nator, spaced from said cathode structure; and means adjacent said cathode and anode structures for establishing a magnetic field in a direction transverse to the discharge path therebetween; said cathode structure including a conductive sleeve provided with an electron-emissive coating; and a heater wire mounted in said sleeve, said heater wire being in the form of a helix coiled in one direction throughout a portion of its length and in the opposite direction throughout another portion of its length.

2. An electron discharge device of the magnetron type, comprising: a cathode structure; an anode structure, incorporating a cavity resonator, spaced from said cathode structure; and means adjacent said cathode and anode structures for establishing a magnetic field in a direction transverse to the discharge path therebe-

tween; said cathode structure including a conductive sleeve provided with an electron-emissive coating, and a heater wire mounted in said sleeve; said heater wire being in the form of a helix having aligned oppositely coiled portions of equal lengths.
